UNITED STATES PATENT OFFICE

ALBERT LOUIS COLMANT, OF CLAMART, FRANCE

FUEL-FEEDING DEVICE FOR INTERNAL-COMBUSTION MOTORS

Application filed September 8, 1927, Serial No. 218,311, and in France September 9, 1926.

This invention relates to improvements in fuel feeding devices for internal combustion motors and more particularly to internal combustion motors which use heavy oils and 5 which are self-igniting.

It is known that many modern carburetors have two air inlets. A slight volume of air is sucked in by the vacuum produced by the motor through a fuel reserve; it produces 10 with this latter an emulsion very rich in fuel, that flows out of the nozzle in the proper place where the pressure is maximum, i. e. in a Venturi double cone; there the emulsion becomes totally or only partly a vapour, and, 15 immediately after by meeting another very important additional current of air, it forms with this latter the optimum explosive mixture which reaches then the working cylinder, so producing definitively from the carburetor the explosive charge of the cylinder.

An improvement consists in sending directly to the cylinder, without any additional quantity of air, the initial emulsion, and in injecting this latter apart in the working cylinder, where it finds only at this moment, the 25 requisite additional volume of air; this latter is also thrown there apart substantially pure, and by any one process as desired.

The features of my invention which I consider novel are pointed out in the appended claims. The invention itself, however, with further objects and advantages will best be understood by reference to the following description with the accompanying drawing 35 where I have shown diagrammatically an example of my invention's application to a standard two stroke cycle engine; in that drawing I have added only the indispensable devices.

40 In the drawing, the reference number 1 shows the working piston, 2 is a piston of a very small diameter which moves inside of its special cylinder 3 and synchronously or about with the piston 1; 4 is the working cylinder; 45 5 an orifice for the input of the emulsion that arrives from the nozzle; 6 a special nozzle giving a very rich emulsion; 7, a valve allowing the input of the emulsion into the small chamber 15; 8 is conduit leading from said 50 small chamber; 9, is an adjustable regulation

valve comprising a stem 12 in threaded engagement with block 13 and having a knurled head 14; 10, is a super-heating conduit and 11 is a fuel spray valve.

The usual admission openings and exhaust- 55 ing openings at the lower dead center are not shown, nor the scavenging method, with pure air (fan) or any other manner, nor the type of ignition (magneto, battery, etc.).

That being granted, the action is as fol- 60 lows: When the pistons go downwards together, a vacuum of a certain value is produced at the upper side of the piston 2. This vacuum is such that the pressure in the cylinder of the piston at the moment when the 65 fuel is introduced is distinctly inferior to the vapor tension or pressure of the fuel (that is the way a value numerically equal to the pressure at which the liquid begins to evapo- 70 rate is called). The emulsion, made up of small spherules of the liquid, then passes instantly into the condition of vapor through the bursting of these spherules. When pis- 75 ton 2 is below the orifice 5, a rich emulsion is taken in. At the same time, the exhausting is produced in the working cylinder, and the burnt gases are scavenged, outwards by pure air, so as to leave this cylinder full of pure air when the piston 1, by its going up, covers the air suction opening, not shown. Like- 80 wise, the small piston 2 covers the orifice 5 and compresses the enclosed emulsion, in its very small upper dead space and in the small chamber 15 and conduit 8. This compression gives rise to the production of heat which 85 is due to the kinetic energy of the particles compressed and which contributes to the rise in temperature and consequently to the passing of the vapor into the condition of dry and very hot vapor. If the adjustable valve 90 9 is completely opened, for example in the case of maximum power, the conduits 8 and 10 form a continuous unobstructed conduit, at the upper dead center, the fuel charge sucked in as an emulsion, which remains so if the motor has its normal compression and the conduit is not superheated. In this case, 95 the valve 11 will be open a little after the middle of the upward course, and then a real transfusion takes place and at any moment 100

the pressure does not succeed in reaching the necessary value for self-ignition.

That is the ordinary two cycle motor but with the following qualities:

5 No loss of pure gas throughout the exhausting opening is to be feared. Then it is possible to scavenge with a great excess of air, and the combustion chamber is cleared of all residues of combustion.

10 But one of the highest advantages of my system is to allow to fix any desired value of the compression without having to fear a premature ignition since the pure air of the working cylinder is compressed apart of the emulsion of the small cylinder, unable to burn for want of air: this emulsion is naturally at a pressure whose value is broadly higher than that of the compression fixed for the working cylinder.

15 But, in this case, that is at the upper dead center, or a little before, that the injection valve 11 will be open in order to project into the combustion chamber the vapour existing in 8 and 10: and it is advantageous to superheat this vapour to in-

20 crease the speed of the combustion as well as to oppose the tendency of the vaporized emulsion to condense itself again under the influence of the compression.

Then I have so obtained a self-ignition motor burning the heavy oils, and the like, but remaining in the explosion cycle, and then able of a quick speed, which is, as known, not the fact for the Diesel cycle.

30 It is impossible to explain here the numerous applications of this feeding process and I will describe only one hereinafter: the qualities of a motor having an expansion long stroke with a short stroke of admission, which has been previously obtained only

35 with a very complex system of rods. Quite the contrary, according to my device, it is sufficient, in order to reach the same qualities, to dispose an adjustable valve upon the bottom of the working cylinder and to maintain 40 this valve opened during a portion of the upwards stroke of the piston, and also to reduce in proportion the ignition chamber.

Furthermore, if this valve is conveniently operated (for example with a sliding cam) 50 the motor becomes a variable compression and expansion one, during its running.

The governing is very easily accomplished by means of the adjustable valve 9. This latter being placed about the middle of the conduit, the small chamber 15 constitutes a constant pressure tank, that is the pressure given by cylinder 3. The quantity of emulsion or charge which cylinder 3 is capable of discharging at a given pressure is greater than 60 the quantity of emulsion necessary for the working cylinder 4 under all conditions.

Also the amount of the charge is varied by the adjustable valve 9 so that the proper amount of charge enters the cylinder 4 to 65 mix with the volume of air in said cylinder

and give the most efficient mixture. It is also necessary that small chamber 15 have a volume so that it can contain at least one full load charge for the working cylinder 4.

70 The pistons 1 and 2 are synchronized, and the recharge or partial recharge of small chamber 15, depending on setting of valve 9, takes place simultaneously with the opening of injection valve 11. For each admission of the cylinder 4, the valve 7 only allows the 75 passage of the charge necessary to produce the power desired in cylinder 4. Whereupon pistons 1 and 2 descend, piston 2 creating a vacuum in cylinder 3, the value of which will depend on the amount of charge delivered 80 to cylinder 4, and which will hold valve 7 in closed position. Consequently, a quantity of emulsion only equal to that previously supplied to cylinder 4 will be sucked into cylinder 3 through orifice 5 and upon compression, 85 since the initial pressure is the same as for the preceding stroke, a pressure equal to that previously existing in cylinder 3 will be created before valve 7 is again opened, injection valve 11 again opens and a charge of the same 90 pressure as before will pass through small chamber 15. Obviously, therefore, the pressure within said chamber 15 will be constant 95 for every setting of the adjustable valve 9 and even for maximum opening of said valve, 100 since said chamber has a volume sufficient to contain one charge at full load.

105 The like process can be applied to a four stroke motor, but the valve 11 is opened only one revolution out of two the small piston will compress one time out of two for nothing practically without any loss of power, the expansion working recovering the compression working of the unused stroke (except the small friction losses).

110 In the example heretofore diagrammatically described, the aspirator-compressor is separated from the working cylinder. But it is obvious that, as well and without any change in the principles of my invention, this aspirator-compressor can be formed by the rear face of the working piston and the front part of the working cylinder, this latter being separated from the crank case by the cross-head guide in this case with a central 115 rod.

120 What I claim and desire to secure by Letters Patent of the United States is:—

1. Method for feeding internal combustion engines which consists of introducing a liquid fuel, finely atomized, into a closed space of variable volume, of so developing this volume at the moment when the fuel is introduced as to create therein a distinctly inferior pressure to the vapor tension of the fuel used, of then compressing in the space the vapor obtained due to this raising of the vacuum, so as to raise the temperature and bring the vapor close to the condition of a perfect gas, of accumulating this dry vapor 125

of constant composition independently of the motor operation in a constant pressure reservoir, of regulating the quantity of this vapor when it leaves the reservoir and prior to the injection into the cylinder of the engine, and
5 of mixing this vapor, after its injection into the cylinder, with an invariable quantity of air determined by the cylinder volume.

2. Feeding device for internal combustion engines, comprising in combination, means
10 for introducing a finely atomized fuel into a closed space, a pump having piston forming a wall of said space so as to be able to vary its volume and creating a vacuum there which carries away the vaporization of the fuel, the
15 vaporized fuel being compressed and super-heated by the other movement of the same piston; a reservoir for the vaporized fuel communicating with said closed space, means for regulating the quantity of constant composition dry vapor contained in the reservoir, placed between said reservoir and the cylinder inlet, and means for injecting this vapor into the cylinder.
